(57) **CLAIM**

The ornamental design for a hosel for a golf club, as shown and described.

DESCRIPTION

FIG. 1 is a perspective view of a hosel for a golf club with the shading on the hosel denoting its contrasting color with the shaft;

FIG. 2 is a side view thereof;

FIG. 3 is a side view thereof;

FIG. 4 is a back view thereof;

FIG. 5 is a front view thereof; and,

FIG. 6 is a perspective view thereof.

The broken line showing is for illustrative purposes only and forms no part of the claimed design.
